SNAP ACTION TOGGLE SWITCH FOR HIGH ALTITUDE USE

Louis A. Yeske, West Hartford, Conn., assignor to The Arrow-Hart & Hegeman Electric Company, Hartford, Conn., a corporation of Connecticut

Filed May 22, 1963, Ser. No. 282,317

7 Claims. (Cl. 200—67)

This invention relates to electric switches and, more particularly, to lever-operated overcenter snap-action electric switches adapted for use at low atmospheric pressures at high altitudes.

Electric switches which perform with complete satisfaction at low levels or low altitudes have been found unsatisfactory for high altitude operation where the air is thin, the atmospheric pressure low and the arcs incident to contact separation and engagement occur more readily and frequently and are harder to extinguish.

Switches which perform satisfactorily over long periods of time and for many thousands of cycles under rated conditions of current and voltage for sea level operation have been found to fail with burnt or frozen contacts after a short period of usage at high altitudes such as 50,000 feet or above.

Switches, when used in aircraft, must not only perform properly at high altitudes, but also at ground level and pressure and at intermediate altitudes and pressures. At all the different altitudes, the temperature, pressure and relative humidity values differ greatly and affect the contact arcing conditions and, hence, vary the life of the switch.

It is an object of this invention to provide an improved quick make and break electric switch capable of use at high altitudes, such as 50,000 feet or more, and also at sea level and intermediate altitudes and which has a long life under such operating conditions.

Another object of the invention is to provide a mounting for a thin sheet metal movable contact blade on a swingable switching yoke to overcome the tendency of the contact to cut into the yoke and become loose and uncertain in its movement when moving between different switch positions.

Another object of the invention is to provide a mounting for a swingable switch yoke, particularly yokes having a fiber glass reinforcement within a synthetic resin body, which mounting will overcome the tendency of the yoke to wear away its bearings.

Another object of the invention is to provide a switch of the foregoing type having its parts made of materials which together cooperate to prolong the life of the switch under adverse conditions of high and low temperature, pressure and humidity, such as occur at high altitudes and at sea level and inbetween.

Other objects and advantages of the invention will occur as it is described in connection with the accompanying drawing.

In the drawing:

FIG. 1 is a section view of a switch with the section being taken along line I—I longitudinally adjacent one wall of the casing so as to show the interior parts.

FIG. 2 is a plan view of the switch shown in FIG. 1 with the cover and handle and spring removed.

FIG. 3 is a perspective view of the center contact of the switch shown in FIG. 1.

FIG. 4 is a perspective view of the end contact of the switch shown in FIG. 1 and an associated plate.

FIG. 5 is a perspective view of the yoke with the movable contacts attached thereto as used in the switch of FIG. 1.

Referring to the drawings, the switch parts are mounted in a switch housing 10 of generally rectangular shape

2

molded from insulating material, such as Glaskyd* (a glass reinforced alkyd molding compound) which is hollowed out to receive fixed switch contact members 20 and 60, a bridging contact 30 mounted on a swingable yoke 40 actuated by an overcenter spring 46 and operating lever 50, all as will be more fully described with respect to their novel details hereinafter. [Herein use of an asterisk indicates the associated word is a Trade Mark name.]

The housing has recesses 14 at each of its four corners for fixed contact members 20 whose form is best shown in FIG. 4. Each fixed contact is stamped from thin sheet metal into U-shape with two wings 23, 25 joined by a central part 21 which, when the contact is inserted in the housing, lies parallel to the end face of the housing 10.

One of the wings comprises a contact 25 for engagement by a bridging contact 30 while the other wing 23 acts as a locating and positioning part to hold the fixed contact member from lateral movement in the recess 14.

From the top edge of the contact member, a tab 27 is bent at a right angle inwardly of the housing with a space between the inner edge thereof and the wing 23 to receive an insulating barrier plate 18 which extends inwardly from the end wall of the housing. The bottom edge of the plate 18 is received in a recess in the floor of the housing. The plate 18 shields the interior operating parts of the switch from arcs drawn during contact separation.

Arc barrier plates 18 preferably are blanked from Teflon*, a fluoro-carbon resin reinforced by glass cloth having very high arc resistance, very high continuous service temperature and low dielectric loss. But a glass-cloth reinforced plate of an epoxy, melamine, silicone or polyester resin may also be used.

The switch as disclosed also has a center contact and terminal member 60 comprising a central portion 62 lying along and perpendicular to the floor of the housing from which contact portions 64 and 66 extend upwardly at opposite ends, and a terminal portion 68 extending down through the floor of the housing.

For bridging the center contact and one end contact or the other, such as 66 and 25 for example, the bridging contact member 30 is mounted on a swingable U-shaped yoke 40. The yoke is preferably made from a sheet of glass-cloth reinforced laminate, such as an epoxy resin, but a melamine, silicone, polyester or fluoro-carbon resin (such as Teflon*) may also be used.

The yoke has trunnions 42 adapted to pivot in opposite seats 12 formed in the upper longitudinal side walls of the housing 10.

Due to the abrasive nature of the glass reinforcing in the housing and the yoke, the trunnions tend to wear away too rapidly. Hence, loose cylindrical electrically insulating bearings 48 are provided on the trunnions. The bearing preferably is made of nylon or some other similar material of self-lubricating nature such as Lexan*, a polycarbonate resin. Experience has shown that such bearings increase the life of the yoke very greatly, up to and beyond the requirements of commercial acceptability.

For swinging the yoke between its two positions, a conventional coil compression overcenter spring 46 is seated at one end on a spring seat or lug 44 on the transverse portion of the yoke while its other end is engaged with the inner end of an operating lever 50 pivotally mounted in a boss or neck 52 upwardly extending from a metal cover plate 54 secured over the top of the housing with an insulating gasket or plate between it and the housing to shield the plate 54 from the interior current-carrying parts of the switch.

The bridging contact member 30 is mounted on the side arms and trunnions of the yoke member and is stamped from thin sheet metal. The member 30 has a

body portion from which contact arms 31 and 33 extend at an oblique angle with respect to one another. Because the contact is stamped from thin sheet metal, it would tend to cut into the yoke and become loose and unreliable in its operation in a relatively short time. To overcome this difficulty, tabs 35, 37 are bent out at right angles from the body of the contact on opposite sides of notches from opposite upper and lower edges of the contact which respectively receive the trunnions 42 and lugs 43.

The lugs extend outwardly from the side arms of the yoke at points spaced from the trunnions and adjacent the transverse portion of the yoke. These tabs, thus, engage the flat side faces of the lugs and of the trunnions so that as pressure is exerted on the bridging contact member by the yoke as the yoke swings from one position to another, the pressure is against a flat surface instead of a sharp edge.

Switches made as above described of the materials as indicated overcome the problems created when switches are used at high altitudes and low atmospheric pressures and also at sea level and normal atmospheric pressures. By the provision of the novel mounting of the yoke as above described, the tendency of the yoke to wear away at its trunnions has been overcome; while the tendency of the movable bridging contact to cut into the yoke has also been overcome by the provision of flat surface abutment of the bridging contact member against the yoke. Likewise, the provision of arc baffle plates of the disclosed materials and the casing of the disclosed material greatly reduce arcing. These details are of great importance and are responsible for operation of the switch up to commercial standards whereas previous materials and constructions have failed and been found to be entirely unacceptable commercially.

Modifications within the scope of the invention will occur to those skilled in the art. Therefore, the invention is not limited to the specific configuration and arrangement of parts as illustrated and described.

What is claimed is:

1. In an electric switch for operation under extreme differences of pressure and temperature as are encountered in jet aircraft operation, an overcenter mechanism comprising a yoke of insulating material having a crank arm, an insulating casing supporting said yoke, an operating lever and an overcenter spring between said lever and yoke for moving the latter, a stamped sheet metal contact mounted on said crank arm, said contact having notches for reception of spaced parts of said crank arm, portions of said contact adjacent said notches being bent to lie flush against the surface of said yoke on opposite sides thereof to receive the thrust of said yoke as it is moved from one position to another by said overcenter spring.

2. In an electric switch, a contact-moving arm of insulating material having a crank portion and a pivot portion, an insulating casing supporting said crank, means to move said arm from one position to another about its pivot portion, a stamped sheet metal contact member having notches therein to receive spaced portions of said contact-moving arm, portions of said contact member adjacent said notches being bent to lie flush against the sur-

face of said crank portion on opposite sides thereof to receive the thrust of said contact-moving arm as it is moved from one position to another and avoid sharp edges of said contact member cutting into said contact-moving arm.

3. In an electric switch as claimed in claim 2, a cylindrical synthetic tough plastic bearing member having self-lubricating properties mounted on the pivot portion of said arm, and a molded insulating casing having a seat receiving said bearing portion.

4. In an electric switch as claimed in claim 3 wherein the contact-moving arm and the casing contain glass-reinforcing material and said bearing member is nylon.

5. A sub-assembly for an electric switch comprising an insulation contact-moving arm having a crank portion and a pivot portion, a thin stamped sheet metal contact member mounted on said arm, said contact member having notches for reception of spaced parts of said crank portion, portions of said contact adjacent said notches being bent to lie flush against the surface of said arm on opposite sides thereof to receive the thrust of said arm as it is moved from one position to another, a cylindrical tough synthetic plastic bearing member having self-lubricating properties mounted on said pivot portion.

25 6. An electric switch as claimed in claim 2 wherein the insulating casing is formed of molded synthetic glass-reinforced plastic material and has a narrow compartment on the floor and one wall of which are formed by portions of said casing, the fixed contact member being in said compartment with its contacting portion lying alongside of one wall of said casing, an arc baffle plate formed of blanked synthetic glass-cloth reinforced plastic material and located on the opposite side of said contact member to form another wall of said compartment, the bridging 30 contact member being engageable and disengageable with said fixed contact within said compartment in proximity to said compartment walls to promote arc quenching.

7. In an electric switch for operation under extreme 40 differences of pressure and temperature such as are encountered in present day jet aircraft, an insulating base, a narrow compartment formed in said base, a fixed contact member in said compartment stamped from sheet metal and having a contact portion adjacent one wall of the compartment and an end portion, an insulating baffle plate forming another wall of said compartment, said fixed contact having a lug bent inwardly of the compartment at its top and a side plate portion extending inwardly from the end portion of said fixed contact spaced from said lug, the top edge of said baffle plate being received 45 and held between said lug and side plate portion.
